US0D1005130S

(12) **United States Design Patent** (10) **Patent No.:** **US D1,005,130 S**
(45) **Date of Patent:** ** *Nov. 21, 2023

(54) **BOTTLE CARRIER**

(71) Applicant: **Christian Runius**, Solna (SE)

(72) Inventor: **Christian Runius**, Solna (SE)

(*) Notice: This patent is subject to a terminal disclaimer.

(**) Term: **15 Years**

(21) Appl. No.: **29/796,108**

(22) Filed: **Jun. 22, 2021**

(30) **Foreign Application Priority Data**

Dec. 22, 2020 (EM) 008364749-0003

(51) **LOC (14) Cl.** **06-04**

(52) **U.S. Cl.**

USPC **D6/525; D9/752**

(58) **Field of Classification Search**

USPC D3/202; D9/455, 751, 752, 753, 719, D9/737, 499, 517, 530; D24/229, 234, D24/230; D6/524, 525, 527, 535, 552, D6/553

CPC B65D 23/10; B65D 23/104; B65D 51/242; A61J 1/16

See application file for complete search history.

(57) **CLAIM**

The ornamental design for a bottle carrier, as shown and described.

DESCRIPTION

FIG. 1 is a front view of a bottle carrier;

FIG. 2 is a left profile view of the bottle carrier;

FIG. 3 is a back view of the bottle carrier;

FIG. 4 is a front perspective view of the bottle carrier;

FIG. 5 is a back perspective view of the bottle carrier;

FIG. 6 is a top view of the bottle carrier; and,

FIG. 7 is a bottom view of the bottle carrier.

The broken lines showing portions of the bottle carrier form no part of the claimed design.

1 Claim, 7 Drawing Sheets
